Borun LLP

(57) **CLAIM**

The ornamental design for a receptacle for granular material,
as shown and described.

DESCRIPTION

FIG. 1 is a front perspective view of a receptacle for granular material of the present invention;

FIG. 2 is a front elevation view of the invention illustrated in FIG. 1;

FIG. 3 is a rear elevation view of the invention illustrated in FIG. 1;

FIG. 4 is a right side view of the invention illustrated in FIG. 1;

FIG. 5 is a left side view of the invention illustrated in FIG. 1;

FIG. 6 is a top plan view of the invention illustrated in FIG. 1; and,

FIG. 7 is a bottom plan view of the invention illustrated in FIG. 1.

The broken lines in the drawings illustrate portions of the
receptacle for granular material and form no part of the
claimed design.

1 Claim, 7 Drawing Sheets
